(57) **CLAIM**

The ornamental design for a door assembly capable of receiving door hinge plate locators, as shown and described.

DESCRIPTION

FIG. 1 is a front, top perspective view of a door assembly capable of receiving hinge plate locators, showing my new design;

FIG. 2 is a bottom plan view thereof;

FIG. 3 is a top plan view thereof;

FIG. 4 is a side view thereof;

FIG. 5 is an opposite side view thereof;

FIG. 6 is a front elevation view thereof; and,

FIG. 7 is a rear elevation view thereof.

The broken lines illustrate portions of the door assembly capable of receiving hinge plate locators that form no part of the claimed design.

1 Claim, 5 Drawing Sheets
